UNITED STATES PATENT OFFICE

BLUFORD W. BROCKETT, OF CLEVELAND HEIGHTS, OHIO, ASSIGNOR TO THE GILKEY PRINTING COMPANY, OF CLEVELAND, OHIO, A CORPORATION OF OHIO

ENVELOPE

Application filed June 30, 1930. Serial No. 464,859.

My invention relates to envelopes or containers for use in inter-party correspondence or communication.

Most envelopes used for this purpose may only be used once or, at least, a relatively few times inasmuch as the addresses of those who are to receive the correspondence or communication have been placed upon some portion of the envelope by means of ink or the like each time the envelope or container was used. That is, no means has been provided whereby the addresses of the sender and receiver and vice versa might be used over and over again selectively.

One object of my invention is to provide an envelope or container that may be used repeatedly in inter-office or inter-party communication or correspondence, the only limitation in the repeated use of the envelope being its reaching a stage of uselessness due to wear of the envelope or container as a whole.

Other objects and advantageous features of my invention may be seen in the following description and one embodiment thereof may be seen in the accompanying drawings wherein similar characters of reference designate corresponding parts, and wherein:

Fig. 1 is an elevation of an envelope or container constructed in accordance with my invention and showing the envelope or container in open position to receive matter or correspondence; Fig. 2 is a view similar to Fig. 1 but showing only a part of the entire envelope or container, the envelope or container being in closed position; Fig. 3 is a view similar to Fig. 2 with the part of the flap or closure of the envelope so arranged as to render a permanent address on the envelope or container visible; and Fig. 4 is a view similar to Figs. 2 and 3 but showing the parts of the flap or closure so arranged as to render another permanent address on the body portion of the envelope or container visible while covering the permanent address visible when the parts are arranged as in Fig. 3.

Referring to the drawings, I have shown one embodiment of my invention as comprising an envelope or container embodying a

55 may be made up of a single piece of material properly folded. For instance, as shown, the envelope or container comprises a single piece of material folded to form a forward side 1 when in folded position and a rearward side 2, the rearward side being so formed that its opposing side edges 3 will overlap the forward side when in folded position making a rigid structure. The rearward side 2 also embodies a flap or closure 4 that may 60 be folded over the upper open side of the envelope or container as shown in Fig. 2 to effectively produce a closed envelope or container in which practically any type of matter may be transferred safely from one point 65 to another.

As shown in Fig. 1, the forward side 1 of the envelope or container is provided adjacent its uppermost edge with an address space 5 containing two addresses, in this instance the name and address of Jack Smith and the name and address of Bill Brown respectively, and the flap or closure 4 is slit to form two flaps 6 and 7 which may be individually and selectively folded under the flap or closure 4 as shown in Figs. 3 and 4 to disclose either one of the hereinbefore mentioned names and addresses when the flap or closure is in closed position. However, if neither of the flaps 6 or 7 are folded under, 80 neither one of the hereinbefore mentioned names and addresses are visible as shown in Fig. 2 whereby the envelope or container may be used in the normal manner by placing other names and addresses thereon with ink 85 or the like.

The flap or closure 4 is provided with suitable fastening means for cooperation with other means on the forward side 1 of the envelope to effectively retain the flap or closure 90 in the closed position shown in Figs. 2, 3 and 4 and maintain each edge of the flaps 6 and 7 that have been folded under as shown in its folded position. This fastening means takes the form of brads 8 on the outermost side of 95 the flap or closure 4 the brads 8 having one end of the cords or strings 9 attached thereto. When in closed position, the cords 9 may be wrapped around brads 10 disposed on the forward side of the envelope or container in 100

such manner as to make a firm connection between the brads 8 and the brads 10 to effectively hold the flap or closure in closed position.

5 As will be apparent, I have provided an envelope or container having a plurality of address spaces disposed thereon in which names and addresses may be permanently placed together with a flap or closure provided with means whereby any one of the names and addresses disposed in the address spaces may be individually and selectively disclosed to view when the flap or closure is in closed position while, at the same time, the remaining names and addresses remain covered. Thus, the envelope or container may be used repeatedly for correspondence or communication between two parties or two points. This is particularly important as an item of 10 saving where a plurality of parties permanently located carry on a large amount of correspondence or communication inasmuch as the only limitation on an envelope or container constructed in accordance with my invention is the normal wear which would render the envelope or container as a whole useless as a receptacle for correspondence or matter.

At the same time, I have provided an envelope or container which may be used in the normal manner and for correspondence or communication between parties other than those whose names and addresses permanently appear on the forward wall 1 of the envelope or container, this being accomplished by so constructing the flap or closure that all of the permanently disposed names and addresses may be hidden from view of an observer if desired. Numerous other advantageous features will be readily apparent.

40 What I claim is:

1. An article of manufacture comprising an envelope embodying a main body portion having a plurality of address spaces thereon, 45 and a flap or closure slit to produce a plurality of flaps individually and selectively movable into and out of a position whereby one of the address spaces on the forward wall of the envelope is visible while the remainder 50 of the address spaces are covered when the flap or closure is in closed position.

2. An article of manufacture comprising an envelope embodying a main body portion having a plurality of address spaces thereon, 55 and a flap or closure slit to produce a plurality of flaps individually and selectively movable into and out of a position whereby one of the address spaces on the forward wall of the envelope is visible while the remainder of 60 the address spaces are covered when the flap or closure is in closed position, and means for securing said flap or closure in closed position.

65 3. An article of manufacture comprising an envelope embodying a main body portion

having a plurality of address spaces on the forward wall thereof, and a flap or closure slit to produce a plurality of flaps individually and selectively movable into and out of a position whereby one of the address spaces on the forward wall of the envelope is visible while the remainder of the address spaces are covered when the flap or closure is in closed position.

70 In testimony whereof I hereby affix my signature.

BLUFORD W. BROCKETT.
